UNITED STATES PATENT OFFICE.

WILLIAM W. CRAWFORD, OF LYNN, MASSACHUSETTS, ASSIGNOR TO GENERAL ELECTRIC COMPANY, A CORPORATION OF NEW YORK.

VAPOR ELECTRIC DEVICE.

1,151,345.

Specification of Letters Patent. Patented Aug. 24, 1915.

Application filed April 12, 1913. Serial No. 760,621.

To all whom it may concern:

Be it known that I, WILLIAM W. CRAWFORD, a citizen of the United States, residing at Lynn, in the county of Essex, State of Massachusetts, have invented certain new and useful Improvements in Vapor Electric Devices, of which the following is a specification.

My invention relates to vapor electric devices, particularly to what is known as the high pressure vapor lamp which consists essentially of a refractory envelop, for example, a fused quartz envelop, in which a mercury arc, or other vapor arc, is operated at a relatively high temperature.

One of the best distinctions that may be drawn between the well known low pressure mercury arc lamp and a high pressure lamp is the following: A low pressure lamp takes about the same voltage and energy at starting as it does at normal operation while a high pressure lamp starts at a much lower voltage and takes less energy at starting than it takes under normal operating conditions when the lamp has come to a final equilibrium. The high pressure lamp as now commonly constructed and proportioned operates with an energy consumption of more than 25 watts per inch in a tube about one-half inch in diameter. In fact, the usual energy consumption is about 80 to 100 watts an inch in a tube of this size.

In the high pressure lamp the arc is not diffused throughout the whole interior of the tube as in the low pressure lamp but is contracted to a comparatively narrow zone in the center of the tube. This arc stream is driven about in the tube causing an undesirable flickering in the light. The use of a contraction in the quartz near the cathode which is a familiar feature of quartz lamps on the market prevents this flickering. In the vertical type of high pressure lamp, this unsteadiness of the arc is considerably more pronounced than in the horizontal type, so much so that one-half the length of the arc or even more, near the cathode, would be constantly moving about inside the tube. A contraction in the quartz near the cathode raises the voltage across the arc, necessitating too great a shortening of the light-giving element or else application of cooling devices, such as fins, neither of which is desirable.

I have discovered that when in the vertical type of lamp, the tube is bent near its

cathode end, so that the bent portion makes an angle of somewhere about 135° with the vertical section of the tube and the sloping roof over the cathode constituted by the wall of the bent portion of the tube leaves a contracted space above the cathode, that steadiness of the arc may be secured.

My invention will be more fully understood by reference to the following description taken in connection with the accompanying drawings, in which—Figure 1 shows my improved vapor lamp in elevation; Fig. 2 is a sectional view at right angles thereto, and Fig. 3 shows a lamp when tilted for starting.

The envelop of the lamp consisting of fused quartz, or similar other refractory transparent material, comprises a vertical section 1 and an inclined section 2 at the lower end of which is a cathode chamber 3. The cathode chamber 3 is filled with a mercury body 4 to such a level that a line drawn vertically through the edge of the mercury meniscus nearest to the vertical section 1 will practically fall within or near the wall of the vertical section, the exposed active surface of the mercury thus being out of line with the arc path in the vertical straight portion of the envelop. The portion of a section 2 which constitutes a sloping roof over the cathode makes an acute angle with the mercury surface. The coöperating anode 5 consists of highly refractory material such as tungsten or molybdenum and conveniently may be formed of wire bent into a flat spiral as indicated in the drawing. The leading-in wires 6 and 7 preferably consist of tungsten sealed by fusion into a sodium-magnesium borosilicate glass having about the same thermal coefficient of expansion, the glass merging gradually into the silica composition thus making the so called "graded seal". The cathode leading-in wire 7 preferably is sealed into a reentrant portion 8 of the envelop so that its end projects into that portion of the cathode chamber which assumes when the tube is tilted the lowest position as shown in Fig. 3. In that manner contact of the leading-in wire with the mercury is secured at all times when the lamp is tilted to bring the mercury into contact with the anode to initiate a flow of current through the lamp.

In a tube having the described construc-

tion of cathode chamber, the unpleasant flickering of the arc is eliminated without changing the voltage and current characteristics of the lamp.

5 A lamp of the character described is described and claimed broadly in applications, Serial Nos. 753,946 and 753,947, filed March 11, 1913, by Dr. E. Weintraub.

What I claim as new and desire to secure 10 by Letters Patent of the United States, is:—

1. A vapor electric device comprising an envelop operable in a vertical position, the lower end of said envelop being bent at an angle, a vaporizable electrode the active surface of which meets at an acute angle a wall of the inclined portion above said electrode and a coöperating electrode in the upright portion.

2. A vapor electric device consisting of an 20 envelop comprising a main tubular section, a cathode chamber and a connecting curved tubular section, an anode in the vertical section, a body of mercury constituting the cathode filling the cathode chamber and being 25 when the main part of the envelop is upright, out of line with the main arc inclosing section and electrical leading-in conductors for said electrodes, said envelop being proportioned and adapted to operate with a vapor pressure at which the arc is contracted 30 to a narrow zone in the center of the arc space.

3. A vapor electric lamp, operating at a voltage higher than the starting voltage, 35 comprising an envelop of refractory material proportioned to be substantially devoid of condensing space outside the arc having a tubular section operable in a vertical position, a cathode container and a connecting tubular section inclined at an angle 40 to said vertical section, an anode near the upper closed end of the vertical section; a

body of mercury in the cathode container, the meniscus of said mercury being out of line with the arc path in the vertical section of the envelop.

4. A mercury vapor lamp comprising a quartz envelop operable in a vertical position and being substantially devoid of condensing space outside of the arc path, an electrode of refractory material near the upper end of said envelop, a mercury electrode at the lower end, the envelop wall above the cathode being inclined at an acute angle to the mercury surface to secure a steady effect upon an arc springing from the mercury.

5. A vapor electric device comprising a tubular envelop curved at one end and being substantially devoid of special vapor condensing means, a solid anode, and an easily vaporizable cathode located at the curved end of said envelop out of line with an axis of the straight portion of the envelop passing through the anode.

6. A vapor electric lamp, comprising a tubular envelop of refractory material devoid of special cooling means outside the arc path comprising a substantially straight portion and an end portion bent out of line with the longitudinal axis, an anode of refractory material and a mercury cathode in said bent portion having substantially all of its exposed surface displaced out of line with the straight portion of said envelop, 75 said exposed surface meeting the wall above at an acute angle.

It witness whereof, I have hereunto set my hand this tenth day of April, 1913.

WILLIAM W. CRAWFORD.
